UNITED STATES PATENT OFFICE

JOSEPH J. SCHERMACK, OF DETROIT, MICHIGAN, ASSIGNOR TO AUTOMATIC MERCHANTISING CORPORATION OF AMERICA, OF NEW YORK, N. Y., A CORPORATION OF DELAWARE

COIN-CONTROL MECHANISM FOR DISPENSING MACHINES

Application filed May 14, 1928. Serial No. 277,774.

This invention relates generally to dispensing apparatus, and has particular reference to coin controlled dispensing apparatus.

It is one of the primary objects of the 5 present invention to provide a multiple coin controlled dispensing machine wherein the coins operate to disengage the latching mechanism and permit actuation of the dispensing mechanism.

10 A further advantageous feature of the present invention is to provide an arrangement of the foregoing character having means for rejecting coins of incorrect denomination, and returning the same to the 15 operator.

With the above, as well as other objects in view, the invention resides in the combinations, construction and arrangement of parts which are particularly pointed out in the 20 claims and which will be made more apparent as this description proceeds, especially when considered in connection with the accompanying drawings.

In the drawings,

25 Figure 1 is a sectional elevational view of a dispensing apparatus constructed in accordance with my invention;

Figure 2 is a perspective view of the operating mechanism;

30 Figure 3 is a fragmentary vertical sectional view on an enlarged scale taken substantially centrally of Fig. 2.

Figure 4 is a front elevational view of the construction illustrated in Figure 2, showing 35 one part of the casing swung to open position;

Figure 5 is an enlarged elevation of the control mechanism as seen from the rear;

Figure 6 is an enlarged elevational view of 40 a portion of the casing illustrated in Figure 4;

Figure 7 is a sectional plan view of a portion of the conveyor actuating mechanism shown in Figure 1;

45 Figure 8 is a top plan view of the mechanism shown in Figure 1 showing the upper portion of the casing in section;

Figure 9 is a view similar to Figure 6 showing 50 a slightly modified form of construction.

In general, the device comprises a casing 10 and a frame 11 for supporting the panels 12 of the casing. Extending inward from the upper and lower front portions of the frame 11 are brackets 13 and 14 carrying 55 the shafts 15 and 16 respectively, which in turn carry two pairs of spaced sprocket wheels 17 and 18 respectively. The sprocket wheels 17 are keyed to the shaft 15 in direct vertical alignment with the sprocket wheels 18, and are connected thereto by means of the flexible linear members or chains 19 and 20.

Extending transversely of the linear members and bridging the space therebetween are 65 a plurality of containers 21 having openings 23 in the front side thereof adapted to register with a corresponding opening 24 in the front wall of the casing 10. Keyed to the shaft 15 to the out side of the right hand 70 sprocket wheel 17 is a third sprocket wheel 25 connected, by means of the chain 26, to a sprocket wheel 27 keyed to the shaft 28, the latter being journaled in a bracket 29 secured to the frame 11 intermediate the brackets 13 75 and 14.

For actuating the shaft 28 to rotate the conveyor, comprising the containers 21 and the chains 19 and 20, I provide a shaft 30 extending transversely of the shaft 28 and carrying 80 at one end a gear 31 adapted to mesh with a corresponding gear 32 keyed to the shaft 28. Positioned upon the opposite end of the shaft 30 is a suitable clutch member 33. Secured to the shaft 28, adjacent the sprocket wheel 27, is a cam member 34 having diametrically opposed slots 35 therein for receiving one end of the spring-influenced dog 36 pivoted to the bracket 29 as at 37. With this arrangement 85 it will be apparent that the conveyor will be normally locked or prevented from moving relative to the shaft 28. As will be understood, the slots 35 are so positioned within the cam member that when the dog 36 is in engagement with one of the slots, one of the 90 containers will be opposite the opening 24 in the casing.

Referring now more specifically to the coin controlled dispensing mechanism for affording 95 actuation of the shaft 28 and accordingly 100

the conveyor, it will be noted that I have provided a cast metal casing 38 comprising complementary sections 39 and 40 hingedly connected together and to the rear side of a door 41 which forms a movable section of the front wall of the casing 10, and is hingedly connected to the frame member 11. The door 41 is provided, adjacent the top edge thereof, with a suitable coin receiving opening 42, 10 adapted to register with a corresponding opening 43 formed in the upper portion 44 of the section 39. As will be apparent from Figure 4 of the drawing, the upper portion 45 of the section 40 cooperates with the portion 15 44 to form a passageway 46 for the coins, the passage-way being provided by oppositely facing ribbed parts or grooves.

Extending forward from the inner face of the body portion 47 of the section 40 is a suitable baffle 48 arranged to cooperate with the side walls 49 and 50 of the section 40, and to cooperate with the section 39 of the casing to divide the body portion 47 into two passages 51 and 52, which as shown communicate with the passageway 46. The passage 51 preferably extends longitudinally of the casing 38 and communicates with a receptacle 53 formed in the door 41 adjacent the lower edge thereof, while the passage 52 preferably 20 establishes communication between the passage 46 and the control mechanism indicated generally by the reference character 54. The lower end portion of the passage 52 designated at 55, is divided into a series of passages, herein shown for the purpose of illustration only, as three, 56, 57 and 58. These 25 passages are of sufficient width to receive the coins and are formed by the spaced baffles 59 and 60, the latter being yieldably supported. 30 The passage 56 is preferably in direct communication or alignment with the passage 52, while the passages 57 and 58 communicate with the latter through the angular passage 61.

45 The section 40 of the casing is preferably cut away as indicated at 62 for receiving the dispensing mechanism 54. This mechanism comprises a shaft 64 journaled in a bracket 65 formed upon the rear side of the section 40 of the casing. Keyed to the shaft 64 is a member 66 having a portion 67 constituting a gear 68, and having another portion 69 of substantially larger diameter than the portion 67 and provided with a series of teeth 70 50 for engaging the ratchet lever 71 pivotally mounted upon the casing as at 72. The ratchet lever is preferably yieldably held in engagement with the teeth 70 by means of the spring 73, having one end connected to the 55 casing and the other end connected to an extension 74 of the lever. As shown, the teeth are provided with inclined cam surfaces 75 and abrupt shoulder portions 76 adapted to engage a laterally projecting finger 77 60 formed on the lever 71 to prevent movement

of the member 76 in a counter-clockwise direction as viewed in Fig. 5. The ratchet portion 69 of the member 66 is further provided with a pair of diametrically opposed recesses or slots 78 and 79 for receiving a laterally projecting portion 80 formed upon the lower end of a dog 81 which, as shown, is pivoted to the rear side of the section 40 as indicated at 82, the width of the recesses 78 and 79 being substantially greater than the width of the laterally projecting portion 80 of the dog 81 so as to permit a limited relative movement between the dog and member 66. The dog 81 is provided, intermediate the pivotal connection thereof, with the casing, and the extension 80 with a laterally inwardly extending portion 83 adapted to project through the opening 62 formed in the section 40 of the casing adjacent the periphery of the member 66 for reasons to be more fully hereinafter described. 75

Projecting upwardly from the pivotal connection of the dog 81, and formed integral therewith, is a lateral portion 84 having a cam surface 85 adapted to engage behind the 80 guide lever 86 in a manner and for reasons to be fully set forth. 90

For yieldably urging the dog 81 in engagement with the ratchet wheel, the spring 87 is provided, having one end connected to the 95 dog as at 88 and the opposite end connected to a pivotal lever 89, which as shown, is operated as by projections 89 to trip a suitable counter illustrated generally by the reference character 90, a link 90^a connecting the counter 100 and the lever 89.

As shown particularly in Figures 3 and 6, the front face of the member 66 is provided with an annular recess 91 forming an annular ring 92 on the member 66, the inner surface 93 of the ring having circumferentially spaced recesses therein adapted to cooperate with the ring 94 to form a plurality of coin receiving pockets designated by the reference characters 95, 96, 97, 98, 99 and 100. 105 The pockets on each side of the center of the ring correspond in number to the number of passages formed in the casing, and as will be readily apparent from Figure 6 of the drawing, the pockets are adapted to register with the passages 56, 57 and 58. It will be further noted from the above figure that the width of the pockets is such as to prevent the coins from passing or falling therethrough. 110

For controlling the number of coins entering the pockets, and for guiding the coins into their respective pockets, the guide levers 86, 101 and 102 are provided. The lever 86 is pivotally connected intermediate the ends thereof to the rear side of the section 40 as 115 at 103, and terminates at the upper end thereof in a forwardly projecting finger 104. This finger is adapted to project through an aperture 105 formed in the section 40 of the casing at the mouth of the passage 52. The 120

130

lever 86 is further provided adjacent the lower end thereof with a second finger 106 adapted to project through a slot 107 formed in the lower end of the passage 58 adjacent the periphery of the member 66. The levers 101 and 102 are also pivoted intermediate the ends thereof to the rear side of the casing and are provided at the upper ends thereof with the forwardly projecting fingers 108 and 109 respectively, adapted to project through suitable openings 110 and 111 formed in the section 40 of the casing at the mouth of the passages 57 and 56 respectively. The levers 101 and 102 are further provided at the lower ends thereof with the forwardly projecting fingers 112 and 113 respectively. These fingers 112 and 113 are adapted to project through suitable slots formed in the casing at the lower end of the passages 57 and 56 respectively. As will be noted from Figure 2 of the drawing, the lever 101 is provided with a laterally projecting pin 114 adapted to rest upon the lever 86 so that movement of this lever will effect a corresponding movement of the lever 101.

For effecting a rotation of the member 66 a gear 115 is keyed to a stub shaft 116 journaled within the section 40 of the casing and connected by a clutch 116^a to the operating handle 117, the shaft 117^a of which is mounted on the door 41. The gear 115 is adapted to mesh with the gear 68 formed on the member 66, and consequently upon rotation of the handle 117 the member 66 and corresponding parts thereof will also be rotated. The gear 115 further carries a clutch part 118 adapted to mesh with the corresponding clutch part 33 secured to the shaft 28 to effect a rotation of the conveyor heretofore set forth.

Referring now to the operation of the device as heretofore pointed out, and assuming that the pockets 95, 96 and 97 are in direct communication with the passages 56, 57 and 58 respectively, and that a coin of the proper denomination is inserted within the coin receiving opening 43, it will be noted that this coin will drop through the passages 46, 52 and 56 directly into the pocket 95. Upon engagement of the coin within the pocket 95 the coin will force the finger 113 outwardly and at the same time move the finger 109 inwardly through the opening 110 to block or close the entrance to the passage 56 so that when a second coin is placed within the opening 43 the coin will strike the finger 109 and be deflected into the passage 57 and corresponding pocket 96. The second coin, like the first mentioned coin, will engage the finger 112 and move the same outwardly and at the same time project the finger 108 through the aperture 111 so as to close the entrance to the passage 57.

Thus from the foregoing it will be apparent that as a third coin is placed in the opening 43, the same will pass through the vari-

ous passages heretofore pointed out and be deflected by both fingers 109 and 108 into the passage 58 and pocket 98, forcing the finger 106 outwardly and at the same time projecting the finger 104 through the aperture 105, blocking the entrance to the passage 52. With this arrangement, if for any reason a fourth coin is placed in the opening 43, the same will be deflected by the finger 104 into the passage 51 and be discharged into the receptacle 53.

With the parts as thus far described each of the pockets 95, 96 and 97 contain a coin, and the extension 80 of the dog 81 is in engagement with the slot 78, and owing to the fact that there is a limited clearance between the extension 80 and the side walls of the said slot, an initial rotative movement of the member 66 will be permitted. Upon rotating the member 66 through the gearing 68 and 115 heretofore set forth, the coin in the sprocket 97 will engage the lateral extension 83 of the dog 81 and swing the latter outwardly about the pivotal connection 82, thus disengaging the extension 80 from the slot 78 and permitting a free rotation of the member 66. In this position of the parts the extension 80 rides along the cam surfaces 75 of the ratchet teeth 70 and reverse movement of the member 66 is prevented by reason of the ratchet lever tooth 77 and shoulders 76 formed on the teeth 70.

By reference to Figure 5 of the drawing it will be noted that as the dog 81 is swung outwardly about the pivotal connection 82 the cam portion 85 will engage beneath the lever 86 and hold the same in a position where the finger 104 is projected through the aperture 105 in the casing, and owing to the connection 114 between the lever 86 and lever 101 this latter lever will also be held in a corresponding position. With this arrangement the fingers 106 and 112 will be retracted from their position adjacent the respective pockets and entirely out of the path of travel of the coins.

From Figure 4 of the drawing it will be noted that as the coin in the pocket 97 assumes a position past the projection 83 on the dog 81, the coin in pocket 96 will move opposite the passage 58, and likewise the coin in the pocket 95 will assume a position opposite the passage 57. As will further be noted in Figures 4, 5 and 6 of the drawing the baffle 60 is pivotally mounted upon the casing as at 119 and extends into close proximity to the periphery of the ring 69 so that as the coins are moved past the baffle 60 the latter is swung upwardly against the action of the spring 120 which engages a pin 120^a projecting from the part 60. With this arrangement it will be apparent that the coins are yieldably held into engagement with the pockets during their movement from the passage 57 to the passage 58.

Revolution of the member 66 is permitted until the pocket 95 is moved past the projection 83 at which time the latter snaps in bringing the dog tooth 80 into engagement 5 with the slot 79 (Fig. 5), and the conveyor is moved a sufficient distance to register one of the containers 21 with the opening 23 in the casing. When the parts are in this position the coins in the pockets 95, 96 10 and 97 assume a position upon the lower side of the ring 69 and are held in engagement with the pockets by means of a track 121 spaced from the periphery of the ring 69 and concentric therewith. Moreover when 15 the parts are in the foregoing position the pockets 98, 99 and 100 assume a position in direct communication with the passages 56, 57 and 58 respectively.

In order to compensate for and avoid 20 faulty operation due to the back lash in the gears, and the relative movement between the dog 80 and slots 78 and 79 when the parts are in the above position, I provide the disk 122 secured to the member 66 and having slots 25 122' and 123 formed in the periphery thereof. These slots are provided with an abrupt surface 124 and an inclined cam surface 125, and are adapted to receive a roller 126 carried by the arm 127 formed upon the lever 128 30 pivoted to the casing as at 129. The roller 126 is preferably held in engagement with the disk 122 by means of the spring 130 connected at one end to the lever 129 and at the opposite end to the casing. The position of 35 the slots 122' and 123 within the disk 122 is so determined that when the series of pockets 95, 96 and 97 are in registration with the passages 56, 57 and 58 respectively, the roller 126 will be in accurate engagement with the slot 40 123, and owing to the abrupt surface 124 of the slot movement of the member 66 in a reverse direction will be prevented and as a consequence an accurate registration between the pockets 95, 96 and 97 and the passages 45 56, 57 and 58 respectively, will be insured. On the other hand, when the roller is in engagement with the slot 122', the pockets 98, 99 and 100 will likewise be held in accurate registration with pockets 56, 57 and 58. 50 When, however, the pockets adjacent the passages 56, 57 and 58 are occupied and the member 66 is rotated, the roller 126 will be forced out of the slot against the action of the spring 130 by virtue of the inclined cam 55 surface 125.

A further advantageous feature of the invention resides in the provision of means for discharging coins of incorrect denomination into the receptacle 53. The means for accomplishing this result comprises a member 60 131 secured to the casing as at 132 and provided with an annular portion 133 adapted to fit within the recess 91 formed in the member 66. As shown, particularly in Figure 65 6 of the drawing, the top surface 134 of the

annular portion is in direct alignment with the pockets formed in the ring and is provided at substantially the center thereof with the laterally projecting inclined surface 135. This latter surface preferably communicates with a downwardly inclined track 136 leading into the passage 51. The arrangement is such that if a coin of incorrect denomination is placed within the opening 43 it will drop through the passages in substantially the same manner as heretofore pointed out, and owing to the fact that the pockets formed in the ring are calibrated or designed to hold a certain type of coin as a nickel for example, which in the present instance is the largest coin that may be placed within the opening 43, the smaller or incorrect coin, such as a cent will pass directly through the pockets and be deflected by the inclined surface 135 on to the track 136 and into the passage 51. Spurious coins will be deflected by means, such as the magnet 51^a (Fig. 4) into the passage 51 at its top.

By reference to Figure 2 of the drawing it will be noted that the disk 122 is provided at right angles to the slots 122' and 123 with a pair of elongated slots or recesses 137 and 138 adapted to receive an extension 139 of the lever 86. The recesses are so positioned within the disk 122 that when one series of pockets is in registration with the passages 56, 57 and 58 the extension 139 will be in engagement with one of the recesses 137 and 138. As shown the latter are provided with inclined walls 140 so that upon movement of the disk 122 the extension 139 will engage the inclined wall 140 of the adjacent recess and swing the lever 86 about the pivotal connection thereof to the casing and incidentally project the finger 104 of the lever 86 through the aperture 105 in the casing to close the entrance and the passage 52. The finger 104 is retained in this position until the other recess assumes a position opposite the extension 139 at which time the finger 104 will be withdrawn and a second series of pockets will assume a position opposite the passages 56, 57 and 58. It will be understood that the rotating coin-holding member is covered by a glassed opening in the door 41.

While in describing the apparatus particular stress has been placed upon the fact that the dispensing mechanism actuates only upon inserting a plurality of coins within the device, it will be noted however, from Figure 9 120 that the device may be readily converted into a single coin controlled system by merely removing the levers 101 and 102 and placing gates 141 and 142 across the passages 56 and 57 respectively. With this arrangement, it 125 will be readily apparent that as a coin is inserted within the opening 43, the same will be deflected by the gates 141 and 142 into the passage 58, with the result that the dispensing mechanism will function in substantially 130

the same manner as heretofore pointed out to rotate the conveyor a sufficient distance to register one of the containers opposite the opening 23 in the casing.

5 While one embodiment of the invention has been described herein somewhat in detail, the construction shown is for illustration purposes only, and the nonessential details herein shown and described should not be considered as limiting in any respect the essentials and principles of the invention. Furthermore, it may be possible to simplify and rearrange the more essential features of the invention without departing from the spirit and 10 scope thereof, and to this end reservation is made to make such changes as may come within the purview of the accompanying claims.

15 What I claim as my invention is:

1. In a multiple coin controlled dispensing apparatus, the combination of a rotatable member having a plurality of coin pockets, means automatically operative when coins are inserted to distribute them in said pockets, said means being maintained in effective position by contact with the coins, preventive means for preventing distribution of coins after a pre-determined number of pockets have been filled, and other means for withdrawing the first-named means from the path 25 of the coins in the pockets when the dispensing apparatus is actuated.

2. In a multiple coin controlled dispensing apparatus having a coin receiving passage, the combination of a series of coin receiving 30 pockets communicating with said passage, means operable upon inserting a plurality of coins corresponding in number to said pockets for distributing one coin into each of said pockets, means operable upon engagement of 35 a coin in the last pocket to close the passage aforesaid, and means for preventing interference of the last recited means with the operation of the dispensing apparatus.

3. In a multiple coin controlled dispensing apparatus, the combination of a rotatable member having a series of coin receiving pockets therein, latching means normally restricting rotation of said member, and means for insuring automatic distribution of coins 45 successively to the pockets, the latching means being released by the coin in the last pocket of the series aforesaid to permit a free rotation of the said member.

4. In a multiple coin controlled dispensing apparatus, the combination of a rotatable member having a series of coin receiving pockets therein, means for latching said member including a pivotal dog engageable with the member, means for insuring automatic 50 distribution of coins successively to the pockets, and means for automatically disengaging said dog from said member to permit rotation of the latter including an extension upon said dog normally positioned adjacent the last pocket of the series aforesaid in the

path of travel of the coins and adapted to be engaged by the coin in the last pocket to swing the dog out of engagement with the said member.

5. In a coin controlled dispensing apparatus, a casing having a coin receiving passage therein, a rotatable member having a coin receiving pocket therein normally registering with the passage aforesaid, a member pivotally mounted upon the casing having a finger 70 adapted to project through the casing into the passage aforesaid to close the same, and means operable by the coin in the pocket aforesaid for engaging the said member to project the finger into the said passage. 80

6. In a coin controlled dispensing apparatus, a casing having a coin receiving passage therein, a rotatable member having a coin receiving pocket therein adapted to register with the passage aforesaid, a member pivotally mounted upon the casing having a projection positioned adjacent an aperture formed in said passage, and a dog having means for latching said rotatable member and for moving the projection aforesaid 90 through the aperture into the passage for closing the same. 85

7. In a coin controlled dispensing apparatus, a casing having a coin receiving passage therein, a rotatable member having a coin receiving pocket therein adapted to register with the passage aforesaid, a member pivotally mounted upon the casing having a finger adapted to project through an opening in the casing into the said passage, and a dog 100 pivotally mounted upon the casing having a portion normally engageable with the rotatable member to latch the same and having another portion operable in the unlatched position of the dog to engage the member aforesaid and project the said finger through the aperture and into the passage to close the same. 95

8. In a coin controlled dispensing apparatus, a casing having a coin receiving passage therein, a rotatable member having a coin receiving pocket therein adapted to register with the passage aforesaid, a lever pivotally mounted upon the casing having a projection positioned adjacent an aperture 110 formed in said passage, and a dog having means for latching said rotatable member and having a portion arranged adjacent to the said pocket for engagement with the coin in the latter, said dog being operable upon engaging the coin to move out of engagement with the rotatable member and to simultaneously engage said lever and move the projection thereof through the aperture aforesaid into the passage for closing the same. 115 120

9. In a multiple coin controlled dispensing apparatus having a divided coin receiving passage, the combination of a series of coin receiving pockets communicating with one branch of said passage, means operative upon 130

insertion of a plurality of coins corresponding in number to said pockets to distribute the coins successively into the pockets, and means operative by contact of the coin in the last pocket to close the aforesaid branch of the passage.

10. In a multiple coin controlled dispensing apparatus having a divided coin receiving passage, the combination of a series of coin receiving pockets communicating with one branch of said passage, means operative upon insertion of a plurality of coins corresponding in number to said pockets to distribute the coins successively into the pockets, means operative by contact of the coin in the last pocket to close the aforesaid branch of the passage, and means for guiding and deflecting coins of lesser diameter than the operative coins into another branch of

20 the passage.

11. In a multiple coin controlled dispensing apparatus, the combination of a casing having an opening, package-holding devices within said casing, rotary members adapted to successively position said package-holding devices at said opening, a series of coin receiving passages, a rotatable member provided with a plurality of pockets adapted to register with said passages, hand actuated devices for rotating said member, and means independent of said hand actuated devices and engageable with said rotatable member to maintain said pockets in accurate registration with said passages, said hand actuated devices being also effective to actuate said rotary members.

12. In a coin controlled dispensing apparatus, the combination of a rotatable member having a plurality of sets of coin receiving pockets, a coin receiving passage communicating with an opening in said casing at one end and having portions registrable with the pockets of each of said sets, said sets successively communicating with said portions of said passage on rotation of said member, locking devices normally preventing such rotation, means operative by the coins themselves for rendering said locking devices inoperative, and detent means for maintaining selective sets of pockets in register with said portions of the coin passage.

13. In a multiple coin controlled dispensing apparatus, a series of coin receiving pockets, automatic operable means for distributing the coins to the respective pockets, means for preventing coins from entering into said pockets after a predetermined number of pockets have received a coin, and means for preventing the last recited means from interfering with the operation of the apparatus.

14. In a coin controlled dispensing apparatus, a combination of a casing having a series of coin receiving passages therein, a rotatable member having a series of pockets

circumferentially spaced about the periphery thereof adapted to register with the passages aforesaid and normally held against rotation, means automatically operable upon inserting a plurality of coins into the apparatus to distribute one coin in each of said pockets, and releasing means for permitting the rotation of said member, said releasing means being adapted to be operated by the coin in the last pocket of said series to receive a coin.

15. In a multiple coin controlled dispensing apparatus having a divided coin receiving passage, a rotatable member having an annular portion with a plurality of circumferentially spaced pockets therein of such a size as to hold a coin of the proper size and to permit an undersized coin to pass toward the central portion of said member, means for registering said pockets with a branch of said passage whereby a coin may be introduced into said pocket for operating said apparatus, and connections between said central portion and another branch of said passage whereby an undersized coin may be returned to the owner thereof.

In testimony whereof I affix my signature.
JOSEPH J. SCHERMACK.
